UNITED STATES PATENT OFFICE

GEORGE P. ANDRUS, OF RAINIER, OREGON

DESIGN FOR A GOLF TABLE

Application filed December 1, 1930. Serial No. 37,858. Term of patent 3½ years.

To all whom it may concern:

Be it known that I, GEORGE P. ANDRUS, a citizen of the United States, residing at Rainier, in the county of Columbia, and State of Oregon, have invented a new, original, and ornamental Design for Golf Table, of which the following is a specification, reference being had to the accompanying drawings, forming part thereof.

Fig. 1 is a perspective end view of a golf table, showing my new design.

Fig. 2 is a perspective view showing the golf table folded and ready for carrying.

I claim:

The ornamental design for a golf table, as shown.

GEORGE P. ANDRUS
